MOLDING MEANS FOR CONCRETE STAVES

Sidney G. Martin, Chicago, Ill.

Application April 6, 1932, Serial No. 603,630

3 Claims. (Cl. 25—121)

The invention relates to improvements in concrete construction and more particularly to a novel form of apparatus for molding staves of precast concrete designed to have interfitting engagement when a number of the units are associated in the proper manner to comprise, as, for example, a cylindrical, conical or flat member.

The lagging or staves formed by the mold of the invention when viewed in cross section consist of a flange having on one face a rearwardly projecting stem portion of a greater width at its outer end than at the junction with the flange, the particular shape of the stem serving to interlock with the latter filled in concrete so as to additionally strengthen the completed pier. In the cylindrical members formed by the lagging the stem portions are directed inwardly and by reducing the interior diameter result in a saving in the metal used in the rings employed for bracing the members.

An object of the invention therefore is the provision of a mold for forming one or a number of staves or lagging at one time so constructed as to be readily assembled or disassembled and which can be adjusted within limits to vary the length and size of the units either in regard to the flange or stem or both.

With these and various other objects in view the invention may consist of certain novel features of construction and operation as will be more fully described and particularly pointed out in the specification, drawings and claims appended hereto.

In the drawings which illustrate an embodiment of the device and wherein like reference characters are used to designate like parts—

Figure 1 is a top plan view of a cylindrical member formed of lagging contemplated by the present invention;

Figure 2 is an elevational view of the cylindrical member showing the same in place in the excavated well with parts of the member being broken away;

Figure 3 is a plan view of the mold constructed in accordance with the invention, and

Figure 4 is a vertical transverse section taken along line 4—4 of Figure 3.

In constructing a concrete pier for foundation work the ground is first excavated forming a well several feet deep which is then lined with staves securely held in place by metal rings. In the use of the lagging formed by the mold of the present invention the excavation would have the appearance such as shown in Figures 1 and 2 wherein the units 10 having a flange 12 and a

stem portion 14 are positioned with the flange in bearing engagement with the earth, while the stem portions are directed inwardly for engagement by the bracing metal rings 16. By means of longitudinal projections 18 and recesses 20 provided on the edges of the flange portion, the staves are interlocked with adjacent units.

After the excavation has been lined with a cylindrical or other shaped member formed of precast concrete staves as above described, the well is then dug to a lower depth and the same process is repeated until rock or suitable foundation is encountered. To complete the pier the well is filled with plastic concrete and by reason of the particular cross sectional shape of the stem portions 14 on the present type of staves the latter and the plastic concrete are securely united, the staves in fact interlocking with the concrete to add to the strength of the completed pier.

The mold for the staves, Figures 3 and 4, is mounted upon a base member 22 and consists in a plurality of forms 24 of substantially inverted U-shape, which are held in position upon the base by end blocks 26 adjustably positioned on the base by inserting a pin 28 through an opening provided in the flange 30 formed integral with the block and into any one of a plurality of openings 32 in the base member. In this manner the forms 24 can be held to the base member and positioned so that the space between the forms is of the desired width for forming the stem portion on the stave. In a somewhat similar manner the partitions 34 are adjustably secured on the forms 24, the ends of the partitions being inserted in the blocks 36 and adjustably positioned on the forms by pins 38 inserted through holes in the flanges of blocks 36 and then through any one of a plurality of openings 40. As more particularly shown in Figure 4 the partitions include a metal blank bent upon itself with one surface of the partition being provided with recesses 42 extending longitudinally of the same to form the interlocking portion on the stave, while the other surface has a projection 44 providing the recess on the stave. The length of the staves formed by the mold can be determined by positioning the plates 46 which are shaped so as to have a tight fitting engagement with adjacent forms 24 and their corresponding adjacent partitions 34.

The present construction of mold can be readily assembled or disassembled as desired with adjustability of the parts being secured so that staves varying in size and length can be fabri-

cated prior to excavation. Portions between forms may be filled in or blocked so as to form the flanges only. Or partitions 34 may be used on base plate without lower forms 24 for this same purpose. By inserting suitable wedge-shaped pieces between the form or partition members, the ends of the lagging may be made bevelled or taper-edged to permit the staves to be driven more easily in case it becomes expedient to adopt this feature in portions of the work. By the adjustability of the sections of the mold a cast unit can be secured having a flange of increased or reduced width, the flange thickness remaining the same. Such a unit is often required in caisson construction since the particular diameter of excavation does not always permit of an assembly of a definite number of staves of definite width.

It is to be understood that I do not wish to be limited by the exact embodiment of the device shown, which is merely by way of illustration and not limitation, as various and other forms of the device will be apparent to those skilled in the art without departing from the spirit of the invention or the scope of the claims.

I claim:

1. A mold for forming concrete staves including spaced forms, a partition removably secured to and located on the upper surface of each form and end plates located between the forms and partitions and being adjustable for varying the

length of the molded stave, said forms being removably secured to a base by means of housings receiving the ends of the forms and having a pin passing through an opening in the housing and base, and said base being provided with additional openings whereby the location of one form with respect to its adjacent form may be varied within limits.

2. A mold for forming concrete staves including spaced elongated forms, a partition located on the upper surface of each form and extending substantially the length of the same, and end plates located between the forms and partitions and being adjustable for varying the length of the molded staves, each partition being adjustable on its form to vary the distance between the partitions, and means securing the forms to a base including housings receiving the ends of the form and having a pin passing through an opening in the housing and base.

3. A mold for forming a concrete stave including spaced members having a substantially horizontal upper surface and inwardly sloping sides, housings receiving the ends of each member and being removably secured to a base, an upstanding partition secured to the horizontal surface of each member, and end plates located between the members and partitions and being adjustable longitudinally for varying the length of the molded stave.

SIDNEY G. MARTIN.
